UNITED STATES PATENT OFFICE

97,142

DESIGN FOR A SUPPORTING BASE

William Millington, Grand Rapids, Mich., assignor to Baker Furniture Factories, Inc., Grand Rapids, Mich., a corporation of Michigan

Application January 31, 1934, Serial No. 50,568

Term of patent 3½ years

To all whom it may concern:

Be it known that I, William Millington, a citizen of the United States, residing at 519 Gladstone SE., Grand Rapids, in the county of Kent and State of Michigan, have invented a new, original, and ornamental Design for a Supporting Base, of which the following is a specification, reference being had to the accompanying drawing, forming a part thereof, in which:

Figure 1 is an elevational view of the supporting base, the essential or dominating features of the design comprising the understructure having

the curved surfaces as indicated and the superstructure which is recessed with respect to the understructure.

Figure 2 is an end elevational view thereof.

Figure 3 is a fragmentary perspective view of one of the legs; and

Figure 4 is a sectional view thereof on line 4—4 of Figure 1.

I claim:

The ornamental design for a supporting base as shown and described.

WILLIAM MILLINGTON.
